PORTABLE IMPACT TOOL OR THE LIKE

Albert C. Koett, 2112 Glenside Ave., Norwood, Ohio

Filed Feb. 25, 1963, Ser. No. 73,683

Term of patent 14 years

(Cl. D54—14)

FIG. 1 is a front perspective view of one side of a portable impact tool or the like showing my new design.

FIG. 2 is a rear perspective view of the other side thereof.

The dominant features of the design are shown in full lines in the drawing.

I claim:

The ornamental design for a portable impact tool or the like, as shown and described.
